HOLDER FOR LAMP BULBS AND SIMILAR ARTICLES

Henry W. Jacobsen, Cleveland Heights, Ohio, assignor to General Electric Company, a corporation of New York

Application June 22, 1944, Serial No. 541,599 1/2

11 Claims. (Cl. 49—64)

1

My invention relates, in general, to article holders or clamps, and more particularly to a holder for supporting tubular lamp bulbs in position during manufacture of the lamp.

In the sealing of tubular electric discharge devices such as fluorescent lamps in general use at present, it is common practice to rest an end of the tubular glass bulb against the rim of the glass stem of the lamp mount after which the contiguous rim portions of the bulb and stem are heated until they fuse and seal together. Where the heating of the glass parts is produced by gas fires, the formation of a good, strong seal is facilitated by resiliently pressing the stem upwardly against the end of the bulb during the sealing process, for instance, by the use of a sealing spindle such as described and claimed in my co-pending application Serial No. 541,519 1/2, of even date, and incorporating a spring-lifted mount support pin. In such case, it is necessary to employ a bulb holder which will grip the bulb firmly and thus prevent it from moving vertically upward under the influence of the upward pressure applied to the bulb by the upwardly spring-pressed stem.

One object of my invention is to provide a holder for tubular articles which will permit ready adjustment of the article therein to any given position but which can be locked to hold the bulb firmly against movement therein.

Another object of my invention is to provide a bulb holder for lamp sealing apparatus which will center the bulb in the sealing head while permitting longitudinal adjustment of the bulb to its proper sealing position relative to the lamp mount, after which the holder can be locked so as to grip the bulb tightly and hold it against movement therein.

Further objects and advantages of my invention will appear from the following description of a species thereof and from the accompanying drawings, in which:

Fig. 1 is a front elevation of a sealing head for electric lamps or similar devices provided with a bulb holder comprising my invention; Fig. 2 is a side elevation of the bulb holder; Fig. 3 is a plan view of the same; Fig. 4 is a front elevation of the same; and Fig. 5 is a fragmentary section of the holder on the line 5—5 of Fig. 4.

Referring to the drawings, the holder 1 ac-

ording to the invention is there shown as applied to a lamp sealing machine head 2 of the type described and claimed in my said co-pending application Serial No. 541,519 1/2, and comprising a spindle 3 rotatably mounted in a turret 4 and provided with a mount support pin 5 for holding a lamp mount 6 up against the lower end of a tubular glass lamp bulb 7. As shown in Fig. 1, the mount pin 5 is resiliently pressed upwardly against the lamp mount 6, during the sealing operation, by a compression coil spring 8 disposed within the spindle and compressed upwardly thereagainst by the engagement of an inner spindle sleeve 9, on which the spring is seated, with a cam track 10. The spindle 3 is provided with two vertically-extending side rods 11, 11 located on opposite sides of the spindle axis and supporting the holder 1.

As shown particularly in Figs. 2-5, the holder 1 according to the invention comprises a U-shaped bracket or body portion 12 having arcuate shaped arms 13, 14 secured at their ends to the vertical side rods 11 of the spindle 3. The bracket 12 is provided with two vertically extending spaced pivot shafts 15 and 16 located on opposite sides of the base of the U-shaped bracket and journaled in bearings 17 on said bracket. Locked to the pivot shaft 15 is a pair of vertically spaced jaws 18 adapted to engage the bulb 7 on one side thereof. The bulb is gripped on its other or diametrically opposite side by a jaw 19 locked to the other pivot shaft 16, the said jaw 19 being located in a vertical position midway between the two vertically spaced jaws 18.

Mounted on and pinned to the pivot shaft 15 at a point between the jaws 18, is a collar 20 having a horizontal ball-end arm 21 extending towards the other pivot shaft 16. The holder jaw 19 is provided with a similar horizontal ball-end arm 22 extending towards the pivot shaft 15. The adjacent ball ends 23 of the arms 21, 22 are received in a notch 24 at the upper end of a lever arm or yoke 25 the lower end of which is keyed or pinned on a horizontal pivot shaft 26 journaled in bearings 27 on the holder bracket 12. Rotation of the horizontal shaft 26 pivots the yoke 25 which, through the ball and socket connection with the arms 21 and 22, pivots the jaws 18 and 19 towards or away from each other in unison.

Fastened at one end to the horizontal pivot

shaft 28 is a more or less horizontally disposed operating arm 28 extending forwardly from the said shaft, closely adjacent one of the side rods 11, to a point forwardly of the said rods. The front end of the operating arm 28 is pivotally connected to a link 29 extending more or less vertically upward from the operating arm. The pivotal connection between the link 29 and arm 28 comprises a pivot pin 30 fastened to the link and slidable within a vertical slot 31 in the arm 28. A lost motion pivotal connection is thus provided between the link 29 and arm 28. A relatively strong or stiff-acting tension coil spring 32, disposed parallel to and behind the link 29 and connected between the arm 28 and a stud 33 on the link, constantly tends to pull the arm 28 upward and the link 29 downward so as to take up the lost motion in the pivotal connection between the said parts and hold the pivot pin 30 at the bottom of the slot 31 in the arm 28.

The upper end of the link 29 is offset rearwardly and pivotally connected by a pivot pin 34 to an intermediate point of a toggle lever or handle 35. The toggle lever 35 is pivotally connected, at a point 36 rearward of the link 29, to an anchor or pivot support block 37 fastened to the upper end of the adjacent side rod 11. In the "open" position of the holder jaws 18 and 19, the operating hand lever 35 extends forwardly in a more or less horizontal direction from its pivot support block 37, as shown in dotted lines in Fig. 2, while in the "closed" or envelope-engaging position of the holder jaws 18 and 19, the operating hand lever 35 extends upwardly from its pivot support block 37 in a slightly backward tilted position, as indicated in solid lines in Fig. 2. The toggle action of the operating hand lever 35 is provided by a tension coil spring 38 connected at one end to the pivot pin 34 on the lever 35 and anchored at its other end to a stud 39 on the holder bracket 12. The point of anchor of the spring 38 to the stud 39 is so located as to cause the axis or direction of pull of the spring to be alternately transposed from a position offset to one side of the hand lever pivot point 36 to a position on the other side of the said pivot point when the hand lever 35 is pivotally moved or "thrown" from its open to its closed position and vice versa.

To facilitate the positioning of the envelope 7 in the holder 1 for proper engagement by the jaws 18, 19 thereof, the holder is provided with a loading guide comprising a pair of vertically aligned bars 40 fastened at one end to, and extending in opposite vertical directions from the holder bracket 12. The free end portions 41 of the bars 40 are bent horizontally forward and have V-notches 42 cut in the ends thereof to thereby provide relatively widely spaced vertically aligned guide jaws for engaging the envelope 7 and substantially aligning it vertically with the spindle 3.

The envelope 7 is inserted in the holder 1 by first pressing the envelope back against the stationary jaws 42 and then pivoting or throwing the toggle hand lever 35 through its "dead center" position to a position slightly therebeyond (dash dot lines in Fig. 2) wherein the jaws 18, 19 first close against the envelope and are pressed into engagement therewith solely by the relatively light force of the toggle control spring 38 acting through the toggle lever 35, link 29, spring 32, operating arm 28 and yoke 25. In such position of the hand operating lever 35, the jaws center the envelope over the flare and

grip the envelope lightly so that the latter can be freely slid down through the jaws 18, 19 until its open lower end butts against the rim of the flare portion 43 of the mount stem 44 resting on the spindle 3. After the envelope is thus properly positioned in the holder jaws 18, 19, the hand operating lever 35 is then pivoted to its fully closed position as shown in full lines in Fig. 2. Due to the lost motion pivotal connection between the link 29 and arm 28, the movement of the lever 35 to its fully closed position lifts the link 29 relative to the operating arm 28 which is held from further pivotal movement by the engagement of the holder jaws 18, 19 with the envelope. Such lifting movement of the link 29 relative to the arm 28 stretches the tension coil spring 32, thereby causing the holder jaws 18, 19 to be tightly pressed into engagement with the envelope by the force of the expanded spring 32 acting on the operating arm 28. The force of the spring 32 is such as to cause the jaws 18, 19 to grip the envelope 7 sufficiently firm to prevent upward sliding movement of the envelope in the holder jaws under the influence of the lifting force which is subsequently applied to the lower end of the envelope by the upwardly spring-pressed mount pin 5 of the spindle.

What I claim as new and desire to secure by Letters Patent of the United States is:

1. A holder for cylindrical articles comprising a bracket, opposed article-engaging jaws one of which is pivoted on said bracket to pivot between an open position and a closed article-engaging position, and jaw closure means including a relatively light-acting spring member and a relatively stiff-acting spring member operatively connected to the pivoted jaw, and actuating means operatively connected to said spring members and movable to sequentially apply the force of first said light-acting spring member and then said stiff-acting spring member to the said pivoted jaw to resiliently press it first lightly and then firmly against the article engaged thereby.

2. A holder for cylindrical articles comprising a bracket, opposed article-engaging jaws one of which is pivotally mounted on said bracket, a lever arm operatively connected to the pivoted jaw to pivot it between an open position and a closed article-engaging position, a relatively light-acting spring and a relatively stiff-acting spring operatively connected to said lever arm, and actuating means operatively connected to said lever arm and springs and movable to first close the pivoted jaw and apply thereto the force of said light-acting spring to resiliently press the pivoted jaw lightly against the article engaged thereby and then upon further movement apply to the pivoted jaw the force of said stiff-acting spring to resiliently press the pivoted jaw firmly against the article engaged thereby.

3. A holder for cylindrical articles comprising a bracket, opposed article-engaging jaws pivotally mounted on said bracket, and actuating means connected to said jaws to pivot them in unison between an open position and a closed article-engaging position, said actuating means comprising a pair of members yieldably interconnected by a spring and relatively movable after closure of said jaws against the article to energize said spring and apply the force thereof to said jaws to resiliently press them firmly against the article gripped therebetween.

4. A holder for cylindrical articles comprising a bracket, opposed article-engaging jaws one of

which is pivotally mounted on said bracket, a lever arm co-operating with said one jaw to pivot it between an open position and a closed article-engaging position, said lever arm having a transverse slot therein normal to its pivotal axis, a member having a pin slidable within said slot to thereby connect the member with the lever arm, and spring means normally maintaining said member and lever arm in a given connected position with one another with the pin engaging one end of said slot, said member being movable relative to said lever arm, after the said one jaw has been pivoted against the article in the holder, to thereby slide the pin away from the said end of the slot and thus apply the force of the spring to said lever arm to cause it to press the said one jaw firmly against the article.

5. A holder for cylindrical articles comprising a bracket, opposed article-engaging jaws pivotally mounted on said bracket, a lever arm co-operating with said jaws to pivot them in unison between an open position and a closed article-engaging position, said lever arm having a transverse slot therein normal to its pivotal axis, a member having a pin slidable within said slot to thereby connect the member with the lever arm, and spring means normally maintaining said member and lever arm in a given connected position with one another with the pin engaging one end of said slot, said member being movable relative to said lever arm, after the jaws have been pivoted against the article in the holder, to thereby slide the pin away from the said end of the slot and thus apply the force of the spring to said lever arm to cause it to press the jaws firmly against the article.

6. A holder for cylindrical articles comprising a bracket, opposed article-engaging jaws one of which is pivotally mounted on said bracket, a lever arm co-operating with said one jaw to pivot it between an open position and a closed article-engaging position, said lever arm having a transverse slot therein normal to its pivotal axis, a link extending transversely of said lever arm and normal to its pivotal axis, said link having a pin slidable within said slot to thereby connect the link and lever arm, a coil spring connected between said link and lever arm for normally maintaining said link and lever arm in a given connected position with one another with the pin engaging one end of said slot and the force of said spring applied to the lever arm in the direction of its jaw-closing movement, said link being movable in the direction of the jaw-closing movement of said lever arm to thereby slide the pin away from the said end of the slot and thus apply the force of the spring to said lever arm to cause it to press the said one jaw firmly against the article.

7. A holder for cylindrical articles comprising a bracket, opposed article-engaging jaws one of which is pivotally mounted on said bracket, a lever arm co-operating with said one jaw to pivot it between an open position and a closed article-engaging position, said lever arm having a transverse slot therein normal to its pivotal axis, a link extending transversely of said lever arm and normal to its pivotal axis, said link having a pin slidable within said slot to thereby connect the link and lever arm, a coil spring connected between said link and lever arm for normally maintaining said link and lever arm in a given connected position with one another with the pin engaging one end of said slot and the force of said spring applied to the lever arm in the direc-

tion of its jaw-closing movement, and toggle means connected to said link and operative through said link and lever arm to first pivot the said one jaw from its open to its closed position against the article in the holder and to then displace the link relative to the lever arm so as to slide the pin away from the said end of the slot and thus apply the force of the spring to press the said one jaw firmly against the article.

10. 8. A holder for fragile articles comprising a body portion, opposed article-engaging jaws at least one of which is pivotally mounted on the body portion, and means for pivoting the pivoted jaw from an open position to a closed article-engaging position comprising an actuating member coupled to said jaw through a lost-motion connection, and a spring member operatively interconnecting said actuating member and said pivoted jaw to take up the lost motion in said connection, said spring being energizable by said actuating member after closure of the pivoted jaw against the article to thereby apply the force of said spring to said pivoted jaw to resiliently press it against the article engaged thereby.

15. 9. A holder for fragile articles comprising a body portion, opposed article-engaging jaws at least one of which is pivotally mounted on the body portion, and means for pivoting the pivoted jaw from an open position to a closed article-engaging position comprising an actuating member coupled to said pivoted jaw through a lost-motion connection, with a relatively stiff spring member operatively connected to said actuating member and said pivoted jaw to take up the lost motion in said connection and energizable by said actuating member to apply closing pressure to said pivoted jaw by movement of said actuating member beyond the position in which it has moved the jaw into engagement with the article,

ected thereto through a lost-motion pin and vertical slot connection, a relatively stiff tension spring connected between said link and horizontal lever arm, an operating arm mounted to pivot in a vertical plane on a fixed pivot adjacent the upper end of said link and pivotally connected at another point thereon to the upper end of said link, and a relatively light spring connected between said operating arm and a fixed point on the body portion of the holder so located that the spring passes a dead center position with respect to the fixed pivot point of the operating arm when said arm is moved to respectively open and close the jaws.

Certificate of Correction

June 20, 1950

Patent No. 2,512,277

HENRY W. JACOBSEN

It is hereby certified that error appears in the printed specification of the above numbered patent requiring correction as follows:

Column 6, line 8, after the word "to" insert *said lever arm to cause it to*;
line 16, for "couple" read *coupled*;
and that the said Letters Patent should be read as corrected above, so that
the same may conform to the record of the case in the Patent Office.

Signed and sealed this 27th day of February, A. D. 1951.
